BEVERAGE VENDING MACHINE

Holy Mortara, Chicago, Ill., assignor to Cole Products
Corporation, Chicago, Ill., a corporation of Illinois

Filed Jan. 21, 1960, Ser. No. 59,134

Term of patent 7 years

(Cl. D52—3)

Fig. 1.

Fig. 2.

Fig. 1 is a perspective view of a beverage vending machine, showing my new design; and

Fig. 2 is a side elevational view thereof both sides being substantially the same, and the back being substantially plain.

The essential features of the design reside in the solid line portions.

I claim:

The ornamental design for a beverage vending machine, as shown and described.
